(57) **CLAIM**

The ornamental design for a cable conduit, as shown and described.

DESCRIPTION

FIG. 1 is a top perspective view of a cable conduit showing my new design;

FIG. 2 is a top view thereof;

FIG. 3 is a side view thereof;

FIG. 4 is another side view thereof;

FIG. 5 is another side view thereof; and,

FIG. 6 is another side view thereof.

The shade lines in the drawings show contour and not surface ornamentation.
